UNITED STATES PATENT OFFICE.

CHRISTIAN F. KLETT, OF PARKESBURG, PENNSYLVANIA, ASSIGNOR OF ONE-HALF TO PAUL ALEXY, OF PHILADELPHIA, PENNSYLVANIA.

SNAP-BUTTON.

1,192,072.

Specification of Letters Patent. Patented July 25, 1916.

Application filed August 11, 1915. Serial No. 45,030.

To all whom it may concern:

Be it known that I, CHRISTIAN F. KLETT, a citizen of the United States, residing at Parkesburg, in the county of Chester and 5 State of Pennsylvania, have invented certain new and useful Improvements in Snap-Buttons, of which the following is a specification.

My invention relates to improvements in 10 snap buttons, the object of the invention being to provide an improved construction of socket member having improved means for securing the same to the material to which the socket member is attached, which 15 insures a rigid, immovable connection of the parts, and results in a strong and durable structure.

A further object is to provide a snap button 20 in which a clamping washer is com-pressed to grip the material to which the socket member is attached, and rigidly hold the socket member in position in the material.

A further object is to improve upon the 25 construction illustrated in Patent No. 1,118,022 granted to me November 24, 1914.

With these and other objects in view, the invention consists in certain novel features of construction and combinations and ar-30 rangements of parts as will be more fully hereinafter described and pointed out in the claims.

In the accompanying drawings: Figure 1 is a view in elevation illustrating the outer 35 face of my improved socket member. Fig. 2 is a similar view illustrating the inner face of the socket member. Fig. 3 is a view in section on the line 3—3 of Fig. 2, showing the socket member in full lines in its shape 40 as it is positioned through the opening in the material, and in dotted lines showing the first bent position. Fig. 4 is a similar view showing the socket member in its com-plete finished state. Fig. 5 is a perspective 45 view of the clamping washer 4, and Fig. 6 is a view in elevation showing a circular form of clamping washer.

My improved socket member comprises 50 four separate and distinct parts, namely, an outer body member 1, an inner holding member 2, an intermediate stud-receiving member 3, and a clamping washer 4, all of which are stamped from sheet metal and in assembling the same no solder or other 55 means is employed either to secure the parts

together or to connect the same to the ma-terial, all of which will be hereinafter more fully pointed out.

The outer body member 1 is the socket member, and has an inwardly turned annu-lar flange 5 to bear against the outwardly 60 projecting annular flange 6 on the holding member 2. The stud-receiving member 3 also has an annular outwardly projecting flange 7 at its inner end which is clamped 65 between the flange 6 and the inner face of body member 1, so as to effectually clamp the members 1, 2, and 3, together.

The holding member 2 is adapted to be projected through an opening 8 in the ma-terial 9, and the opening 8 is smaller than 70 the member 2, so that in projecting the lat-ter through the opening, the material around the wall of the opening is bent in-wardly as shown at 10.

The clamping washer 4 is appreciably larger than the holding member 2, and bears 75 against the inner face of the material 9 and through this clamping washer the inwardly 80 bent portions 10 of the material project as shown clearly in Fig. 3. The washer 4 in cross section is curved or convex so that when the member 2 is flared outwardly and 85 bent against the washer 4, it will serve to flatten the washer 4, causing the hole in the latter to reduce in area, and thereby 90 compel the inner wall of the washer to grip or bite into the inwardly projecting portion 10 of the material 9 as shown clearly in Fig. 4. Furthermore, by reason of this bend-ing outwardly of the member 2 and then flattening the same as far as permitted by 95 the several parts, the inwardly bent portion 10 of the material 9 is caused to encircle or cover the inner edge of the clamping washer 4, and hence the material is rigidly secured and the socket member is held against move-ment.

The stud-receiving member 3 is provided with a plurality of stud-receiving sockets 100 11, if desired, which would cause the socket member to be of somewhat elongated ellipti-cal shape or if desired, this socket member may be circular, in which event a circular clamping washer 12 will be employed as 105 shown in Fig. 6.

By employing the clamping washer 4, and bending the holding member 2 against the washer, I am enabled to secure the socket member to the material without any danger 110

of the member moving in the opening in the material, but on the other hand, I effectually secure the socket member and the material together, so that there can be no 5 independent movement and no tearing apart.

Various slight changes might be made in the general form and arrangement of parts described without departing from my invention, and hence I do not limit myself to the 10 precise details set forth, but consider myself at liberty to make such changes and alterations as fairly fall within the spirit and scope of the appended claims.

15 Having thus described my invention, what I claim as new and desire to secure by Letters Patent is:

1. A snap button, comprising a stud-receiving socket member and a holding member adapted to be projected through the material to be secured, and a clamping washer against which the holding member is bent, said clamping washer arched in cross section and adapted to have its opening contracted 25 by the pressure of the holding member thereagainst and to clamp the material against the outer face of the holding member, substantially as described.

2. A snap button member comprising a 30 stud-receiving member, a holding member, said stud-receiving and holding members having outwardly projecting flanges, a body member clamping the said flanges, said holding member adapted to be projected through 35 an opening in the material to which it is to be secured, whereby the material is caused to bend against the outer face of the holding member, and a clamping washer having its opening adapted to be contracted by the 40 pressure of the holding member when the

end of the latter is flared outwardly against the same, said clamping washer adapted to clamp the material against the outer face of the holding member, substantially as described.

3. A snap button member adapted to be projected through the material to which it is secured, a holding member constituting a part of the snap button, and a clamping washer adapted to be located between the 50 holding member and the material to be secured, said washer having its opening adapted to be contracted by the holding member, whereby its inner wall is adapted to clamp the material against the snap button member, substantially as described.

4. A snap button comprising a stud-receiving member, a holding member, said stud-receiving and holding members having outwardly projecting flanges, a body member clamping the said flanges, said holding member adapted to be projected through the material to which it is to be secured, whereby the material around the holding member is bent, a clamping washer having a central 60 opening large enough to receive the bent portion of the material around the holding member, said washer curved in cross section, and said holding member adapted to be bent inwardly against the washer to flatten the 65 same and to cause the inner wall of the washer to grip the bent portion of the material, substantially as described.

In testimony whereof I have signed my name to this specification in the presence of 70 two subscribing witnesses.

CHRISTIAN F. KLETT.
